UNITED STATES PATENT OFFICE.

PERCY H. THOMAS, OF EAST ORANGE, NEW JERSEY, ASSIGNOR TO COOPER HEWITT ELECTRIC COMPANY, A CORPORATION OF NEW YORK.

CURRENT-RECTIFIER.

SPECIFICATION forming part of Letters Patent No. 776,565, dated December 6, 1904.

Original application filed May 6, 1903, Serial No. 155,925. Divided and this application filed August 23, 1904. Serial No. 221,816.
(No model.)

To all whom it may concern:

Be it known that I, PERCY H. THOMAS, a citizen of the United States, and a resident of East Orange, county of Essex, State of New Jersey, 5 have invented certain new and useful Improvements in Current-Rectifiers, of which the following is a specification.

My invention relates to devices for obtaining a flow of current in a given direction from 10 alternating electromotive forces.

In its physical embodiment the device herein described consists in general of an inclosing chamber containing a gas or vapor and separated electrodes, one or both usually consisting of mercury. When properly constructed and operated, a current may be caused to pass in one direction only through such a device, the device opposing so great resistance to flow of current in the opposite direction as 20 to practically prohibit such flow.

The particular subject of this invention is a novel form and construction of such a device, the object being to provide means for keeping the device cool, maintaining the proper purity 25 and density of the gas or vapor within the chamber, and adapting it to transmit currents of large quantity.

In carrying out my invention I provide means for conducting a large amount of current into and from the device with relatively small resistance and also means for carrying away from the chamber heat generated therein and for withdrawing from the chamber any excess of vapor and maintaining the vapor in 35 the proper condition. Among the means employed for these purposes are tubular extensions of the main body of the container, these extensions being filled wholly or partially with mercury if that be the substance of either or 40 all of the electrodes. In the present instance the ends of the tubular extensions are open and the mercury columns inside the tubes are sustained by a pressure higher than atmospheric pressure, while at the same time means 45 are provided for transferring a portion of the mercury from one tubular extension to the other after causing it to pass through a cool-

ing device, whereby the passage of the mercury will cause heat to be carried away from the chamber and will also cause any excess of 50 vapor to be withdrawn, as stated above. I may provide artificial cooling means; but this is not always necessary, as the mercury will ordinarily be naturally cooled during its passage from one tubular extension to the other. 55 I also provide a pump of suitable form for causing the circulation by positive means of mercury into and out of the main chamber. In this way a circulation of the mercury within the chamber is obtained.

During the process of circulation the mercury may be cooled by artificial means, as by one or more refrigerating-coils placed at a proper point or points in the cycle, or I may accomplish the cooling effects by causing the 65 mercury to enter or reenter the chamber in the form of spray. These two means may, if desired, be combined or other cooling devices may be employed.

My invention will be described more particularly in connection with the accompanying drawing, which represents a vertical section showing one form of apparatus.

In the drawing, 1 represents the inclosing chamber containing a suitable gas or vapor, 75 which for convenience will be referred to as "mercury-vapor." This container is provided with two tubular extensions 2 and 4, containing columns of mercury, which constitute, respectively, the positive and negative terminals of the device. The tubes are here represented as terminating in vessels 5 and 6, into which lead-wires 11 and 12 dip. The outer ends of the tubes 2 and 4 are open, and the mercury columns are sustained within 85 them by atmospheric pressure.

In the present instance the tubes 2 and 4 are bent upward, as shown, the outer portion of the bend being carried to a height above the barometric limit, whereby a pressure in 90 excess of the barometric pressure is applied to the terminals inside the container 1.

The vessel 6 is connected by a pipe 8 with any suitable form of pump 9, the outlet of

which is connected with a pipe 10, which ends just above the vessel 5.

In the operation current is led from the conductor 11 into the mercury in the vessel 5, then passes through the mercury column contained in the bent tube 2 and through the vapor in the chamber 1 to the mercury contained in the tube 4, and thence to the vessel 6 and out by way of the conductor 12. In this case it is assumed that the conducting gas or vapor in the chamber 1 is under high pressure, and to compensate for such excessive pressure the weight of the mercury above the limit of atmospheric pressure is increased by the weight of the mercury in the outer sides of the tubes. The main thing to be obtained is that the column of conducting fluid, whatever the nature of the fluid is, may serve as a balance between the external and the internal pressures. To secure good cooling effects I may surround the pipe 8 with a water-jacket 20.

The term "extension" or "extensions" as used in this specification does not necessarily mean tubes formed in one piece with the chamber 1 or formed on the chamber. Such extensions may be tubes secured in the walls of

the chamber by any means which will prevent leakage.

This is a division of my application filed May 6, 1903, Serial No. 155,925, the said application being itself a division of an earlier application filed February 4, 1903, Serial No. 141,804.

I claim as my invention—

The combination with an inclosing chamber and a conducting gas or vapor therein having a pressure higher than the external pressure, of an electrode consisting of a conducting fluid having its outer terminal exposed and subjected to external pressure, the said outer terminal being located above the barometric height, whereby a balance is secured between the internal and external pressures by adding to the effect of normal external pressure the weight of a portion of the conducting fluid.

Signed at New York, in the county of New York and State of New York, this 12th day of August, A. D. 1904.

PERCY H. THOMAS.
